[57] ABSTRACT

The pulverized coal combustion zone at the mouth of each burner of a furnace comprising a number of such units, is viewed by a sensor of molecular carbon radicals, producing a fluctuating output signal when the corresponding burner unit is in operation. Such signal passes through a differential amplifier and line driver to a differential variable preset gain amplifier by way of a capacitor coupling; and from the amplifier to a zero crossing (Schmitt Trigger) detector. The resulting pulsed signal of the detector goes to a monostable multivibrator having a pulse width adjustment. The one-shot output pulses of the multivibrator pass by way of an adjustable slope control on analog integrator of such one-shot pulses, having a DC output of one selected voltage range for actual combustion "ON" and a lower selected voltage range for combustion "OFF". Such DC voltage output goes to a one-bound comparator, and then through a variable delay circuit to either a Red combustion "ON" or a Green combustion "OFF" lamp.

PULVERIZED COAL COMBUSTION DETECTOR

SUMMARY OF THE INVENTION

The frontal area of combustion of a pulverized coal burner in a boiler furnace is scanned by a sensor of molecular carbon radicals in a strategically located probe position. When combustion is present, the sensor produces a fluctuating output, that passes through a differential amplifier and line driver, and then by way of a capacitor and line amplifier, to a zero crossing detector. The output of the latter is amplified and goes to a one-shot multivibrator provided with a pulse width adjustment for optimum burner combustion conditions. The output of the multivibrator passes through an integrator slope control to an analog integrator of the one-shot pulses having a direct current output range of relatively low voltage for flame "OFF", and a somewhat higher voltage range for flame "ON". Such direct current output is applied to a one-bound comparator, the output of which goes through a variable delay circuit to either a red or a green lamp which corresponds to an "ON" or "OFF" combustion condition, respectively.

By adjusting the slope of the integrator the detector can be adjusted to deal with combustion with low emission, as is present during boiler start-up, or when the burners are operating at low loads.

Gas turbulence at any particular burner position is dealt with by varying the time constant of the integrator. In case the integrator time constant cannot be made long enough for any particular situation, then the variable "ON-OFF" delay is utilized at the output of the comparator. Combustion gas turbulence is a function of the particular burner being viewed, as well as the type of boiler comprising such burner.

Should a particular combustion scintillation content be low in high frequency on account of either the type of coal being burned, or the consistency characteristic of the pulverized coal, then the monostable multivibrator output pulse width can be lengthened to compensate therefor. Conversely, the pulse width can be shortened when there is a large amount of high-frequency in the complex scintillation signal of the combustion, and the unit becomes saturated.

In accordance with the present invention the system can be adjusted to indicate "OFF"/"ON" conditions for combustion having low emission characteristics, such as those present at boiler start-up, or with burners running at low loads, by virtue of the integrator slope adjustment. Also, undesirable gas turbulence at any particular burner position on a boiler can be dealt with by varying the integrator time constant which can last up to 35-40 seconds, and if the integrator time constant cannot be made long enough for a given situation, the variable "ON"/"OFF" delay can be adjusted at the output of the comparator to do so.

BACKGROUND OF THE INVENTION

Flame detectors for infrared, visible and ultraviolet radiation are well known; but until the present invention none was suitable for detecting the combustion of pulverized coal in a boiler furnace because of the particular stoichiastic flame front movement of such flames.

One prior system utilized a flame detector having an ultraviolet cell and a silicon photovoltaic cell in a common housing for monitoring the flames of a pulverized

coal and oil burner. Such silicon voltaic cell circuit is typical of the prior art, furnishing a signal indicative of the amplitude of the high frequency flicker of the sighted flame and the illumination level thereof. The flame "ON-OFF" circuit of the photovoltaic cell separated the fluctuating and direct components of the cell output signal and applied them to separate channels. The output signal was first obtained by adjustment of a switch to selected resistors and passed through a coupling capacitor to an AC amplifier. Such output was then increased in voltage by a power amplifier and converted to a DC signal by a demodulator circuit. The DC signal then went to a relay for indicating the "ON-OFF" condition of the flame.

Some of the general problems relating to pulverized coal flame detection prior to the present invention include the following:

The main problem with all flicker detectors that previously have been used is that they do not cope effectively with the spatial movement of the flame front. This movement is due to turbulence within a furnace and must be considered entirely stoichiastic.

The present system uses electronic memory means to solve this spatial variance problem. The memory is centered in the integrator circuit, such that if the high frequencies in the flame front move momentarily out of the field of view of the cadmium sulfide sensor, the time constant of the integrator is such as to "remember" the flame "on" condition until the flame front or combustion zone moves back into the field of view of the sensor element.

The instant invention deals with the chemiluminescent molecular carbon radicals formed by coal undergoing combustion at the burner mouth. The first derivative of the signal given off by the short-lived molecular carbon radicals is proportional to the multiple mono-pole acoustic energy generated by the pulverized coal particles undergoing combustion. Thus, detection of light energy from molecular carbon radicals can be correlated with combustion acoustic energy. In the present invention this principle is used to establish the presence or absence of true combustion of pulverized coal particles.

BRIEF DESCRIPTION OF THE DRAWINGS

The above brief description as well as further objects, features, and advantages of the present invention will be more fully appreciated by reference to the following detailed description of a presently preferred but nonetheless illustrative embodiment in accordance with the present invention when taken in connection with the accompanying drawings wherein:

FIG. 1 is a circuit diagram of a pulverized coal flame detector illustrative of the invention;

FIG. 2 is a block diagram of the detector with adjustments shown in more detail;

FIGS. 3 and 4 are graphs corresponding to recordings of voltage wave forms at several points in the system;

FIG. 5 is a representation of the one-shot multivibrator output pulse wave form; and

FIGS. 6 and 7 are graphs of representative recordings of the voltage levels of the comparator input and variable delay output, respectively.

DESCRIPTION OF THE PREFERRED EMBODIMENT

As shown in FIG. 1, a pulverized coal combustion burner mouth area 10 in a boiler 12 containing a number of such areas is viewed or scanned by a cadmium sulfide probe 14 containing a cadmium sulfide sensor 16 comprising a photovoltaic type photo cell. The sensor 16 preferably is a Cd.S.R.C.A Type SQ2502 sensor head that is connected to a differential amplifier 18 and a line driver 20. The amplified output of the latter is fed to a variable preset gain line amplifier 22 by way of the coupling capacitor 23.

From differentiating amplifier 22 the combustion signal goes to a zero crossing Schmitt trigger type detector 24 which converts the fluctuating signal to pulses of differing duration, width, and spacing. Such pulses are transmitted to a one-shot monostable multivibrator 26 which includes a capacitor 28 and an adjustable resistor 30 connected to a stabilized source of constant voltage 32, for adjusting the pulse width duration of the output of multivibrator 26. The multivibrator input circuit includes an edge amplifier gates 32 and 34.

The output pulses of the multivibrator 26 go to an integrator 36 by way of an adjustable resistor 38 constituting an integrator slope control. A capacitor 41 is connected in shunt with the integrator 36 and resistor 38, and the capacitor 41 is provided with a reset switch 42. From integrator 36 the signal goes to a one-bound comparator 39 by way of a buffer circuit 40. A sighting meter 42 is also connected by way of a meter driver 44 to the output of buffer circuit 40.

The output of comparator 39 goes to an adjustable delay circuit 46 having one selected voltage output going to a green or combustion "OFF" light 48, and another going to a red or combustion "ON" light 50. The comparator 39 is provided with a variable reference voltage circuit comprising an adjustable resistor or potentiometer 54 and a source 56 of direct current for comparison purposes. The DC level should generally be about 1.3 volts to 1.4 volts for the combustion "ON" condition; while a combustion "OFF" condition is about 1.0 volts to 1.2 volts or lower. The comparator 39 distinguishes and acts upon such levels causing the corresponding light to be energized, i.e., green: combustion "OFF", and red: combustion "ON", for example.

The delay circuit 46 acts to delay the actuation of either the red-combustion "ON" and green-combustion "OFF" lights 48 and 50, respectively. The delay is variable, and is a function of the particular burner being monitored, with the delay usually being about 10 to 15 seconds.

Referring to FIG. 2, sensor head H, for detecting molecular carbon radicals, is suitably positioned with respect to one burner of a pulverized coal fired multiburner boiler 60. The output signal of the head H goes to the differentiating amplifier 18 by way of resistor R, and capacitor C1. The output of the amplifier 18 in turn is applied to the Schmitt trigger peak detector 24, the output of which goes through an amplifier 62 to the one-shot multivibrator 26.

The multivibrator 26 comprises a timing circuit 64 including a switch 66 adapted to contact a selected one of four taps 68 corresponding to four resistors 70 of different resistance values. The switch 66 is set according

to the particular burner operating conditions of the flame being monitored.

The integrator 36 is provided with slope control adjustable resistor 38. The sighting meter 42 is connected to the output of integrator 36 by way of meter drive 44, and is calibrated to indicate the DC voltage thereof, i.e. 1.3 to 1.4 volts for combustion "ON", and 1.0 to 1.2 volts for combustion "OFF". The comparator 39 is provided with a comparative voltage supply circuit 52 10 that is adjustable by means of potentiometer 54.

The delay units allow time delays for flame "ON" 15 flame "OFF" indication to be variable, and proportional to the burner fuel input rate. They comprise thermally actuated relay contacts. The integrator is an operational amplifier, having its input and output terminals connected together by an integrating capacitor 37. In this way the amplifier output is the time integral of the input signal.

The one-shot multivibrator comprises an integrated 20 circuit which produces a predetermined length pulse at the output terminal each time the signal at the input to the "AND" gate 32 goes positive with respect to ground. Pulse length at the output is fixed by components 28 and 30. If an input signal goes positive during 25 the active regime of the multivibrator it is ignored.

The sensor head includes the Cd.S photoconductive cell connected in a resistive bridge, the output of the bridge being differentially fed to an operational amplifier for voltage gain, and high common mode signal rejection. The signal from the voltage amplifier is then applied to a line driver so that the signal may be received 30 remotely at the indicator equipment.

FIG. 3 shows a voltage/time recording of typical combustion "OFF" and "ON" signals 80 and 82 at the 35 output terminal A, FIG. 1, of the line driver 20 of the system, corresponding to the input of capacitor 23 by way of example.

FIG. 4 shows the output pulses 84 of the zero crossing detector 24, FIG. 1, at terminal B thereof and the corresponding combustion "ON" complex input signal 40 82 at terminal A.

FIG. 5 is an enlarged and exaggerated representation 45 of the wave form 86 of the pulsed output of the monostable multivibrator at terminal C thereof, FIG. 1, showing variable mark to space ratio.

The reference (comparison) voltage level 88, and signal (combustion "OFF") voltage level 90 are shown 50 in FIG. 6. As can be seen in FIG. 1, the voltage readings were taken across points D, of the input of comparator 39.

At the output E, FIG. 1, of the delay 46, FIG. 1, the combustion "ON"/flame "OFF" voltage recordings are shown in FIG. 7, respectively, for the output E and delay 46 of FIG. 1.

The one-shot multivibrator 26 is triggered by positive 55 going excursions (being of sufficient slope) from the combustion scintillation signal as sensed by the sensor 16. Because the peak detector or Schmitt trigger is intrinsically a zero-crossing detector, the output of the one-shot is derivative of the first differential coefficient 60 of the input signal, due to the fact that the differentiating amplifier will attenuate signal components not due to combustible gases being evolved in the combustion front. The one-shot pulse length is increased or decreased as a function of burner primary and secondary air conditions, and also as a function of pulverized fuel particle size.

The analog integrator is used to sum the area under the individual one-shot pulses. The DC level so derived was around 1.3 volts to 1.4 volts DC for a flame "ON" condition, while a flame "OFF" condition was about 1.0 volts to 1.2 volts DC or lower.

The system is based on detecting radiation from chemiluminescent radicals and uses a standard cadmium sulfide detector unit, the maximum sensitivity of which is in the vicinity of .512 micron. The electronic signal conditioning can be summarized as follows: When the photocell output voltage reaches a certain threshold value and in addition is rising at a certain minimum rate, the zero-crossing detector is triggered, giving a positive change in the voltage output of the zero-crossing detector. When the photocell output voltage again crosses the threshold value but in the negative direction, the voltage from the zero-crossing detector is returned to its original value. The leading edge, or positive-slope part, of the zero-crossing detector's output is used to trigger the one-shot multivibrator, which produces a square-wave voltage pulse of constant duration and amplitude, but variable repetition rate. The output of the one-shot multivibrator is integrated with respect to time. If this integral falls within a certain range, which can be translated into the number of threshold crossings, positive fuel ignition is indicated.

The predominant frequencies detected by the sensing element in several multiple-burner coal-firing installations fall in the range of 20-100 Hertz. By "predominant" it is meant the frequency at which the photocell's output energy fluctuations are at a maximum. However, it must be noted that the photocell actually detects a very broad range of frequencies, some of which fall outside the range of response of the recording equipment.

The DC output from the integrator is applied to the one-bound comparator such that combustion "ON" - combustion "OFF" levels can be distinguished and acted upon.

The variable delay appropriately delays the actuation of the green/red - combustion ON/OFF lights. Delay is adjustable and is a function of the particular burner being monitored, but is usually around 10 to 15 seconds.

A latitude of modification, change and substitution is intended in the foregoing disclosure and in some instances some features of the invention will be employed without a corresponding use of other features. Accordingly, it is appropriate that the appended claims be construed broadly and in a manner consistent with the spirit and scope of the invention herein.

What is claimed is:

1. A combustion detection system for pulverized coal fired burners, comprising:
  - a combustion sensor circuit for producing a high frequency output signal corresponding to radical radiation of the pulverized coal undergoing combustion at the mouth of the burner;
  - a differential amplifier circuit for differentiating such radical radiation signal whereby the latter is directly proportional to the sonic energy given off by the coal particles undergoing combustion;
  - a zero-crossing peak detector coupled to said amplifier circuit for converting the high frequency output signal thereof to pulses of varying duration corresponding to such sonic energy;

- 5 a one-shot monostable multivibrator connected to said detector for changing such pulses to one-shot pulses of uniform duration;
- 10 an integrator acting to integrate such one-shot pulses into a direct current output, the voltage level of which corresponds in one range to the "OFF" condition of such combustion, and in a different range to the "ON" condition thereof;
- 15 a comparator for distinguishing between such ranges; and
true combustion "ON" and "OFF" indicators operated by said comparator as distinguished from flame detection per se of the burners.
- 20 2. A combustion detector system as defined in claim 1, in which
means are provided for delaying the operation of said "ON/OFF" indicators by said comparator from 10 to 15 seconds.
- 25 3. A combustion detection system as defined in claim 2, in which
said delay means comprises means for adjusting the duration of such delay to match the particular gas turbulence characteristics of the combustion of the burner being monitored.
- 30 4. A combustion detection system as defined in claim 1, in which
said sensor comprises a photocell which is sensitive to radiation at 0.512 microns wave length,
35 said zero-crossing peak detector comprises a Schmitt trigger unit, and
said multivibrator comprises means for adjusting the duration of the output pulses thereof for optimum operation of the system in accordance with the H/F content of the output signal of the sensor.
- 40 5. A combustion detection system as defined in claim 4, in which
said integrator comprises means for adjusting the integrator slope for programming the system to handle combustion of relatively low emissivity such as those present at start-up, as well as burners operating at low loads.
- 45 6. A combustion detection system as defined in claim 5, in which
said integrator also comprises means for adjusting the integrator time constant for avoiding undesirable effects of gas turbulence in the combustion such as those due to the position of the combustion of the burner being monitored.
- 50 7. A combustion detection system as defined in claim 6, in which
adjustable delay means are also provided for delaying the "ON"/"OFF" operation of said indicators by said comparator in case said integrator time constant cannot be made long enough to avoid the effects of undesirable gas turbulence in the combustion being monitored.
- 55 8. A combustion detection system as defined in claim 7, in which
the sensor of molecular chemiluminescent carbon radicals includes a cadmium sulfide type photoconductive cell circuit responsive to the molecular carbon radical intensity variations produced by spatial movement of the combustion front of a pulverized coal burner subject to turbulence within the furnace containing such burner; and
60 the integrator provides an electronic memory such that when the flame front of the burning coal being

monitored moves out of the field of view of the cadmium sulfide sensor the time constant of the integrator is such as to "remember" the flame "ON" condition until the combustion zone moves back into the field of view of the sensor.

9. A combustion detection system for pulverized coal fired burners having a zone at the burner mouth from which pulverized coal particles undergoing combustion radiate short-lived chemiluminescent molecular carbon radicals, the first derivative of the signal given off thereby being proportional to the multiple monopole acoustic energy generated by such pulverized coal particles undergoing combustion, comprising:

a sensor circuit for producing a high frequency output signal corresponding primarily to such radical radiation of the pulverized coal undergoing combustion in such zone at the mouth of the burner, including

a probe containing a photoconductive cell for viewing the particles of coal undergoing combustion in such zone of the burner, to pick-up such radical radiation, and

differential amplifier circuit means connected to said

cell for electrically differentiating the radiation given off by such radicals, whereby such output signal is directly proportional to the multi-source sonic energy given off by the coal particles undergoing combustion in such zone at the mouth of the burner.

10. The invention as defined by claim 9, including a zero-crossing peak detector circuit coupled to said sensor circuit for converting the high frequency differentiated output signal thereof to pulses of differing duration, width and spacing, which are proportional to the multi-monopulse sound radiation fields given off by the burning coal particles in such zone.

11. The invention as defined by claim 10, including digital circuit means for converting such pulses to one-shot pulses of uniform duration, then integrating such one-shot pulses into a DC output having combustion "ON" and "OFF" levels, comparing such levels, and indicating the corresponding condition of actual combustion as distinguished from detection per se of the pulverized coal particles.
